UNITED STATES PATENT OFFICE

ELWOOD S. BURCH, OF DOWAGIAC, MICHIGAN, ASSIGNOR TO ROUND OAK FURNACE COMPANY, OF DOWAGIAC, MICHIGAN

DESIGN FOR A FURNACE

Application filed February 9, 1933. Serial No. 47,168. Term of patent 3½ years.

To all whom it may concern:

Be it known that I, ELWOOD S. BURCH, a citizen of the United States, residing at Dowagiac, in the county of Cass and State of Michigan, have invented a new, original, and ornamental Design for a Furnace, of which the following is a specification, reference being had to the accompanying drawing, forming part thereof, in which

Fig. 1 is a front perspective view, and Fig. 2 is a rear perspective view of a furnace, showing my new design.

I claim:

The ornamental design for a furnace, as shown.

ELWOOD S. BURCH.
